CABINET

Robert G. Mager, Ann Arbor, Mich., assignor to Robert Mager Associates, Inc., Ann Arbor, Mich.

Filed Nov. 17, 1961, Ser. No. 67,577

Term of patent 14 years

(Cl. D33—19)

FIGURES 1, 2 and 3 are a perspective view, a left side elevational view and a right side elevational view, respectively, of a cabinet showing my new design.

The dominant features of my design reside in the portions shown in full lines.

The rear of the cabinet is substantially plain and unornamented.

I claim:

The ornamental design for a cabinet, as shown and described.
